UNITED STATES PATENT OFFICE.

ABNER A. PLUMMER, OF PUTNAM, CONNECTICUT, ASSIGNOR OF ONE-HALF
TO IRVING H. ROBERTS, OF SAME PLACE.

STEAM-BOILER.

SPECIFICATION forming part of Letters Patent No. 285,923, dated October 2, 1883.

Application filed July 12, 1883. (No model.)

To all whom it may concern:

Be it known that I, ABNER A. PLUMMER, a citizen of the United States, residing at Putnam, in the county of Windham and State of Connecticut, have invented a new and useful 5 Steam-Boiler, of which the following is a specification, reference being had to the accompanying drawings.

This invention relates to steam-boilers; and 10 its object is to provide a boiler possessing superior advantages in point of simplicity, inexpensiveness, durability, and general efficiency.

In the drawings, Figure 1 is a perspective 15 view of my improved boiler. Fig. 2 is a vertical sectional view of the same, taken from side to side. Fig. 3 is a vertical sectional view taken from front to rear. Fig. 4 is a horizontal sectional view taken through one 20 of the water-sections.

Referring to the drawings, A designates the boiler proper, which is preferably cylindrical in form and vertically placed on a suitable base, B, forming the ash-box, and having the 25 grate C of the fire-chamber at its top.

The boiler A is formed of several sections, D, each comprising a water space or chamber, E, and a fire-space, F, these spaces being arranged to extend over the area of the section, 30 while the water-chamber is formed with a vertical flue or opening, G, through it. These sections D are entirely separate, and are preferably cast solid, so that there will be no joints to leak, and are placed one upon another, so 35 that the fire-flues G between the fire-spaces F will be alternately at the front and rear of the boiler. By this arrangement the fire and products of combustion will pass from the fire-chamber through the first flue G, thence 40 horizontally through the fire-space F to the front end of the boiler, then up through the next flue G and horizontally back to the rear of the boiler again, and so on up and from front to rear until it passes off through the exit-flue H. 45 The first or lower section, D', and the next section, D'', have their fire-spaces arranged to occupy the whole central portion to form the furnace-chamber I of the boiler, while their water spaces or chambers are arranged cir- 50 cumferentially around the fire-space, and the section D'' is provided with the fire-door J, as

shown. The middle sections, D, have the horizontal fire-spaces and corresponding water-chambers, the fire-spaces being connected by the alternate flues G, formed through the 55 water-chambers, and the top section, D'', has the steam-dome K, and has the exit-flue H, extending from its fire chamber or space.

The usual safety-valves, gages, steam-pipes, &c., can be arranged as desired on the boiler, 60 and the front plate, L, of the latter is preferably provided with doors M, through which the flues can be cleaned.

At one side of the boiler is arranged a vertically-disposed stand-pipe, N, that is provided at its top with a gage, O, and is connected with the water-spaces at their bottoms by auxiliary pipes P, by which the said stand-pipe will receive the water for which it is adapted. At the other side of the boiler is 70 arranged a corresponding stand-pipe, Q, that is connected with the water-spaces near their tops by auxiliary pipes R, and is adapted for steam. The dome K will furnish a sufficient quantity of dry steam. 75

The operation and advantages of my invention will be readily understood. The separable sections of the boiler are only connected by the stand-pipes, so that, by unscrewing, the latter can be taken out for purposes of substitution, &c., or more sections can be easily 80 added, so as to make the boiler high enough to utilize the full heating-power of the furnace at the bottom. By reason of the arrangement of the stand-pipes, the one for water being 85 connected with water-chambers at the bottom and the one for steam being connected at the top, a circulation is caused by which a more efficient operation is secured. Besides, the arrangement is very simple and can be conveniently operated. 90

I claim as my invention—

1. The combination of sections comprising a water space or chamber, said sections being arranged one above the other, the water stand-pipe connected with the water-chambers near their bottoms, and the steam stand-pipe connected with the water-chambers near their tops, whereby a circulation is secured, substantially as set forth. 95

2. As an improvement in boilers, the combination of the boiler proper, consisting of the 100

detachable sections placed one on top the other, and each comprising a fire-space and a water chamber or space, through which is provided a fire flue or opening, the furnace being
5 formed in the bottom chambers or sections, and the steam-dome and exit-flue in the top sections, the water stand-pipe disposed vertically and connected with the water-spaces by auxiliary pipes or branches leading to near the
10 bottoms of the water-chambers, and the steam stand-pipe arranged at the opposite side of the

boiler, and connected to the water-chambers by branches leading to near the tops of said chambers, substantially as and for the purpose set forth.

In testimony that I claim the foregoing as my own I have hereto affixed my signature in presence of two witnesses.

15 ABNER A. PLUMMER.
